UNITED STATES PATENT OFFICE.

MAX LANGER, OF CHARLOTTENBURG, NEAR BERLIN, GERMANY, ASSIGNOR TO
SIEMENS & HALSKE A.-G., OF SIEMENSTADT, NEAR BERLIN, GERMANY, A
CORPORATION OF GERMANY.

TELEPHONE SYSTEM.

1,404,396.

Specification of Letters Patent. Patented Jan. 24, 1922.

Original application filed June 23, 1914, Serial No. 846,813. Renewed April 10, 1919, Serial No. 289,134. Patent No. 1,322,247, dated November 18, 1919. Divided and this application filed November 13, 1919. Serial No. 337,745.

To all whom it may concern:

Be it known that I, MAX LANGER, a German citizen, and resident of Charlottenburg, near Berlin, Germany, have invented certain new and useful Improvements in Telephone Systems, of which the following is a specification.

This invention relates to telephone systems, the present application being a division of my application Serial No. 846,813, filed June 23, 1914; renewed as Serial No. 289,134, April 10th, 1919, now Patent No. 1,322,247, Nov. 18th, 1919.

The object of this invention is to enable the metering of calls in telephone systems in which connections are established over selectors or switches and testing takes place over the talking wires. For this purpose measured service devices and circuits are included in the telephone system with a view to enabling the metering of calls, when the receivers are replaced to the hooks at the stations.

Another object of the invention is to provide means whereby the calls may be metered as soon as the called subscriber takes off his receiver from the hook.

In the drawings two modifications are diagrammatically shown by way of example.

Figs. 1—3 represent a telephone system in which the calls are metered as soon as the calling subscriber as well as the called subscriber replace their receivers to the hooks, respectively.

Figs. 4, 2, 5 represent a telephone system in which the metering takes place when the called subscriber takes off his receiver from the hook.

In the telephone system shown in the drawings all relays and contacts operated thereby are represented in their normal positions.

The operation of the telephone system shown in Figs. 1—3 is as follows:

When the receiver is removed from the switch hook at the station N_1 , the following circuit is closed: ground, battery, left hand winding of relay R_1 , back contact t_3 , line conductor a , station N_1 , line conductor b , back contact t_2 , right hand winding of relay R_1 , ground. When the wipers of the line switch VW are advanced until the private

wiper cv engages an idle trunk line, whereupon a circuit is completed from ground through battery, working contact r_1 in parallel through the relays T and Z , wiper cv , line c , resistance w_1 through resistance w_2 , back contact m_1 to ground, and, at the same time, in parallel through winding 1 of relay C , primary off-normal contact h_1 to ground. In this circuit the meter relay Z is not energized whereas the relays T and C are energized and, therefore, the working contacts t_4 , t_6 , t_7 are closed. Consequently the following circuit is completed: ground, battery, relay A_1 , left hand winding of the differentially wound relay X , trunk line a , working contact t_6 , station N_1 , trunk line b , working contact t_7 , right hand winding of relay X , relay B_1 , ground. Since the back contact t_5 is opened the rotary magnet Dv of the line switch VW becomes de-energized. The voltage drop caused by the closing of the working contact t_4 does not suffice to energize the relay Z . As soon as the calling subscriber operates his calling dial in the usual manner the relay B_1 is grounded at the station N_1 . When the relay B_1 is momentarily de-energized the differentially wound relay X is energized. As the calling dial returns to its normal position the relay B_1 is again energized by the following circuit: ground, battery, working contact x_1 , relay B_1 , ground. The relay B_1 practically remains energized until the talking connection is released. The relay X also closes its working contact x_2 , thereby preparing a circuit for the vertical magnet H_1 from ground, battery, vertical magnet H_1 , secondary off-normal contact wk_1 , back contact a_1 of the relay A_1 , working contact x_2 to ground. When the dial is returning to its normal position the current impulses sent over the trunk line a are transmitted to the vertical magnet H_1 of the first selector I.GW by the operation of the working contact a_1 of the relay A_1 . As soon as the dial has returned to its normal position the ground at the station N_1 is removed and the armature of the relay X released, whereas the relay B_1 remains energized. During the current impulses the off-normal contact h_1 in the circuit of the winding 1 of the relay C is opened at the first step of the shaft of

the first selector I.GW. The winding 1 of the relay C remains grounded, however, in a circuit extending over its own working contact c_1 , working contact x_3 of the relay X, and the 5 back contact m_1 of the relay M₁. At the first step of the shaft of the first selector I.GW the primary off-normal contact h_7 is closed. Since, however, the back contact b_{12} has been opened by the relay B₁, the relay S 10 remains de-energized. After the last impulse for the first digit being transmitted the ground at the station N₁ is removed. Therefore, the relay X de-energizes and opens the circuit of the relay C at the contact x_3 . At 15 the same time the working contact x_2 is opened, the vertical magnet H₁ having been de-energized by the opening of contact a_1 .

The rotary magnet D₁ will now become 20 energized in a circuit from ground, battery, interrupter U_b₁, relay D, back contact c_2 , working contact b_1 to ground, and rotates the wipers of the first selector I.GW until the relay C is energized again. This occurs at the moment the wipers j_1 , j_2 engage a 25 trunk line VL leading to an idle second selector II.GW (see Fig. 2) thereby establishing the following circuit: ground, battery, relay A₂ of the second selector II.GW, primary off-normal contact h_2 , back contact p_1 , wiper j_1 , working contact b_2 , second winding 2 of the relay C, back contact c_3 , wiper j_2 , back contact p_2 , primary off-normal contact h_3 , back contact a_2 , ground. When the relay C thus operating as a 30 private magnet is energized the circuit of the rotary magnet D₁ is broken at the contact c_2 . At the same time the contacts c_1 , c_4 , c_5 are closed thereby extending the connection to the selector II.GW and establishing 35 a holding circuit for the relay C from ground, battery, working contact t_4 in parallel through relay Z and relay T, wiper c_7 , resistance w_1 , winding 1 of the relay C, working contact c_1 , secondary off-normal contact wk_1 , back contact m_1 to ground. This holding circuit remains established until the connection is released. 40 As soon as the shaft of the first selector I.GW is rotated the secondary off-normal contact wk_1 is opened thus preventing a re-energization of the vertical magnet H₁.

The relay A₂ upon energizing closes the 45 working contacts a_3 , a_6 , a_7 and opens the back contacts a_2 , a_5 , a_{11} . By the closing of the working contact a_3 a guarding potential is established extending from ground, battery, relay B₂, working contact a_3 , primary off-normal contact h_3 , back contact p_2 , trunk line b (see Fig. 2), wiper j_2 (see Fig. 60 1), working contact c_5 , working contact a_7 , back contact v_1 , resistance w_7 , back contact s_1 to ground. The relay A₂ remains energized in the following circuit: ground, battery, relay A₂, primary off-normal contact k_2 , back contact p_1 , wiper j_1 , working 65 con-

tacts c_4 , a_4 , back contact v_2 , resistance w_6 , back contact s_1 , ground.

When now the calling subscriber operates his dial for the second digit the relay X is energized again and, therefore, both 70 trunk lines a and b in the first selector I.GW are grounded at x_4 . During the second digit of current impulses the relay A₁ is de-energized, accordingly, thereby the 75 working contacts a_4 and a_4' are broken and the ground is removed from the trunk lines a and b at the contact x_4 . The relay B₂ remains, however, energized in a circuit over the resistance w_3 and the contact x_4 . During the current impulses the relay A₂ becomes de-energized, accordingly. Therefore, the contact a_3 is opened and the contact a_2 is closed. The opening and closing of these contacts does not effect, however, a de-energization of the relay B₂ since its 85 circuit is closed by the working contact b_2 . By the closing of the contact a_5 the circuit for the vertical magnet h_2 of the second selector II.GW is completed: ground, battery, vertical magnet H₂, working contact b_4 , back contact a_2 , ground. As soon 90 as the vertical magnet H₂ is energized the wipers j_3 , j_4 of the second selector II.GW are operated. At the first step of the shaft of the second selector II.GW the primary 95 off-normal contact h_2 is opened. The relay A₂, however, remains energized in a circuit over the resistance w_4 as well as over the working contact b_7 .

After the last impulse for the second 100 digit being transmitted the ground at the station N₁ is removed. Therefore, the relay X becomes de-energized so that the working contact x_4 is opened, thus the ground is removed from the trunk lines a , 105 b , and the relay B₂ de-energized. Since the working contact b_4 is opened the vertical magnet H₂ becomes de-energized. The contact b_5 being closed a circuit is prepared for the rotary magnet D₂. The relay A₂ remains energized in a circuit extending from 110 ground, battery, relay A₂, resistance w_4 , back contact p_1 , wiper j_1 , working contacts c_4 , a_4 , resistances w_5 , w_6 , back contact s_1 to ground. Since the relay A₂ is energized 115 and the relay B₂ de-energized a circuit is established for the rotary magnet D₂: ground, battery, interrupter U₂, rotary magnet D₂, working contact a_6 , back contacts p_3 , b_5 , primary off-normal contact h_4 , 120 ground. The wipers j_3 , j_4 of the second selector II.GW are rotated until they engage a trunk line leading to an idle third selector III.GW.

The circuit for the rotary magnet D₂ remains established until the contact p_3 is opened. The contact b_5 in the same circuit remains closed since the relay B₂ does not attract its armature again before the winding 2 of the relay P₁ is energized. 125 130

- The test circuit of the second selector II.GW is as follows: ground, battery, relay A_3 , primary off-normal contact k_{13} , back contact p_{13} , trunk line a , wiper j_3 , working contact a_7 , back contact b_6 , winding 2 of relay P_1 , wiper j_4 , back contact p_{19} , primary off-normal contact k_{31} , back contact a_{14} to ground. The wipers of the second selector II.GW are advanced until an idle selector II.GW are advanced until an idle
- 10 third selector III.GW is found. A third selector is idle if the back contact a_{14} of the relay A_3 is connected to ground, and if the trunk line a is connected by the relay A_3 of the third selector III.GW to battery. As
- 15 soon as an idle third selector III.GW is found the following circuit is established: ground, battery in the third selector III.GW, relay A_3 , primary off-normal contact k_{13} , back contact p_{13} , trunk line a ,
- 20 wiper j_3 , working contact a_7 , back contact b_6 , winding 2 of the relay P_1 , wiper j_4 , trunk line b , back contact p_{19} , primary off-normal contact k_{31} , back contact a_{14} , ground. In this circuit the relay P_1 is energized and
- 25 the operating circuit for the rotary magnet D_2 opened at the contact p_3 . Therefore, the second selector II.GW extends the connection to the third selector III.GW. The relay P_1 in the second selector II.GW being energized the contacts p_1 and p_2 are opened and the contacts p_4 , p_5 , p_6 , p_2' are closed. The connection is thus extended by the working contacts p_5 and p_2' to the third selector III.GW.
- 30 The operation of the third selector III.GW in extending the connection to the connector LW is substantially the same as of the second selector II.GW.
- 35 As soon as an idle connector has been found the test relay P_2 of the third selector III.GW and the relay A_4 of the connector LW are energized. Therefore, the back contact a_8 is opened and the working contact a_9 closed, so that the relay B_4 is now included
- 40 in a circuit over the working contact a_9 . Thus the relays A_4 and B_4 are energized. If now the subscriber operates his dial for the fourth digit the relay X of the first selector I.GW is energized thereby closing the
- 45 contact a_4 . During the interruption of the loop at the station N_1 the relay B_4 remains energized during the emission of impulses in the following circuit: ground, battery, relay B_4 , back contact y_1 , working contact b_8 , back contact p_7 , trunk line b , wiper j_6 , working contacts c_5 , a_4' , x_4 , ground. The relay B_4 being energized the contact b_9 becomes closed and the vertical magnet H_4 energized in the following circuit: ground, battery, vertical magnet H_4 , back contact u_1 , working contact b_9 , back contact a_9 , ground, so that the shaft of the connector is operated. At the end of the impulses sent out by means of the dial at the station N_1 the relay
- 50 X becomes de-energized and, therefore, the contact a_4 is opened. The trunk line a is now included in a circuit extending from ground, in the first selector I.GW, back contact s_1 , resistances w_6 , w_5 , working contacts a_4 , c_4 , wiper j_1 , working contacts p_5 , p_6 , winding 1 of relay P_1 , relay A_2 in the second selector II.GW, battery, ground. Another circuit is established from contact p_5 , trunk line a , wiper j_2 , working contact p_{10} , relays P_2 and A_3 , battery, ground, and a third circuit extending from working contact p_{16} , trunk line a , wiper j_5 , back contact p_8 , resistance w_8 , back contact y_2 , relay A_4 , battery to ground. In the second selector II.GW the relay A_2 as well as the relay P_1 remain energized although the winding 2 of the relay P_1 has become de-energized. Therefore, the relays A_1 , A_2 , A_3 and A_4 are energized.
- 55 Since no current is flowing in the trunk line b in the connector LW the relay B_4 releases its armature. Therefore, the back contact b_{10} is closed and the relay U energized in the following circuit: ground, battery, relay U , back contact b_{10} , working contact a_{10} , primary off-normal contact k_5 , ground. The primary off-normal contact k_5 has been closed at the beginning of the operation of the shaft of the connector LW. The relay U closes the working contact u_2 and remains energized independently of the condition of the relay B_4 until the primary off-normal contact k_5 is opened by the operation of the connector LW when returning to normal position. By the operation of the relay U the back contact u_1 is opened and the working contact u_3 closed. Since the relay X becomes de-energized the working contact a_5 is opened so that the slow acting relay V becomes de-energized. If, therefore, the contact v_1 of the relay V is closed sometime afterwards the following circuit is established again in the first selector: ground, back contact s_1 , resistance w_7 , back contact v_1 , working contacts a_4' , c_5 , wiper j_2 , working contact p_2' , wiper j_4 , working contact p_{17} , wiper j_6 , back contact p_5 , working contact a_9 , back contact y_1 , relay B_4 , battery, ground.
- 60 When the subscriber rotates his dial for the last digit of current impulses the relay X is energized again. The contact a_4 in the first selector I.GW is closed and the contact v_1 opened. Thus the circuit over the trunk line b remains established since this line remains grounded by the contact a_4 . The circuit over the trunk line a is intermittently interrupted in accordance with the interruptions caused by the dial switch. The relays A_1 and A_4 in the first selector I.GW and in the connector, respectively, become de-energized in accordance with the interruptions referred to. The rotary magnet D_4 in the connector LW is energized by the following circuit: ground, battery, relay D_4 , working contacts u_3 , b_9 .

4
back contact a_9 , ground. Together with the rotary magnet D_4 , the slow acting relay V_1 is energized by the circuit: ground, battery, relay V_1 , working contacts v_3, b_9 , back contact a_9 , ground.

The last series of current impulses having been sent out the contact x_4 in the first selector is opened, so that the trunk line b is currentless. Therefore, the relay B_4 in 10 the connector becomes de-energized and releases its armature. The relay V_1 in the connector, however, still remains energized for some time since it is slow-acting. A testing current for the connector is then 15 established from ground over back contacts m_3, g_1 , working contact v_3 , back contact b_{11} , relay P_3 , wiper cw of the connector LW , contact g of the line switch VW of the 20 called subscriber N_2 , relay T_2 , primary off-normal contact k_{11} , battery, ground. The test relay P_3 of the connector is energized 25 thereby. Sometime afterwards the contact v_1 of the slow-acting relay V in the first selector LGW will become closed. The relay B_4 in the connector is thereby energized again. The test relay P_3 of the connector LW remains energized since it has been included in a holding circuit by its working contact p_{15} . By closing this contact p_{15} a 30 portion of the winding of the relay P_3 is short-circuited so that the called line is rendered busy. By the energization of the test relay P_3 the working contact p_8' is closed and the back contacts p_7, p_8 opened. The 35 relay A_4 remains energized over the contact y_2 , resistance w_{11} , contact p_8' , trunk line a , wiper j_5 , working contact p_{16} , wiper j_3 , working contact p_5 , wiper j_1 , working contacts c_4, a_4 , resistances w_5, w_6 , back contact 40 s_1 to ground. At this moment no circuit is established over the trunk line b . If then the relay V_1 in the first selector LGW becomes de-energized and the contact v_1 closed a current will flow over the trunk line b in 45 the following circuit: ground, contact s_1 , resistance w_7 , back contact v_1 , resistance w_3 , working contact c_5 , wiper j_2 , working contact p_2' , wiper j_4 , working contact p_{17} , wiper j_6 , resistance w_{10} , working contact a_6 , back 50 contact y_1 , relay B_4 , battery, ground. It is immaterial whether the circuit through the relay B_4 includes the resistance w_{10} or not since the relays A_4 and B_4 do not affect the line-connection if they are simultaneously 55 energized or de-energized. Thus the bridge in the connector comprises the following circuits: one circuit from ground, battery, relay A_4 , contact y_2 , resistance w_{11} , working contact p_8' to trunk line a and another 60 circuit from ground, battery, relay B_4 , back contact y_1 , working contact a_6 , and in parallel over back contact b_8 , resistance w_{10} , to the trunk line b . As soon as the test relay P_3 becomes energized the contact p_9 in the 65 circuit of the call relay L is closed as well

as the contacts p_{10} and p_{11} in the trunk line a, b . Since the relay V_1 is slow-acting it is still energized when a calling circuit is established for the called station N_2 as follows: ground, battery, winding 2 of the call 70 relay L , working contacts v_4, p_9 , back contacts y_3 , primary off-normal contact k_6 , ground. The contact k_6 has been closed at the first movement of the connector LW . The relay L opens its contacts l_1, l_3 and 75 closes the contacts l_2, l_4 . Therefore, a calling current is sent to the called station N_2 as soon as testing takes place. As soon as the relay V_1 has become de-energized additional periodic calling current impulses are 80 sent by the excited winding 1 of the relay L in the following circuit: ground, battery, interrupter Ub_4 , winding 1 of the relay L , working contact p_9 , back contact y_3 , primary off-normal contact k_6 , ground. These periodic calling current impulses are sent to the station N_2 until the called subscriber takes off his receiver from the hook. When the called subscriber takes off his receiver from the hook the following circuit is closed: 85 ground, battery, winding 1 of the relay Y , back contact l_2 , working contact p_{11} , station N_2 , working contact p_{10} , back contact l_1 , relay F , ground. The relays F and Y are energized in this circuit and the back contacts y_1 and y_2 opened and the working contacts y_5 and y_6 closed, respectively. The relays A_4 and B_4 now become de-energized, and an inductively wound relay O having 90 the middle of its winding grounded is connected to the trunk lines a and b . The ground connection at the relay O in the connector is now in parallel with the ground at the contact s_1 in the first selector at the 95 talking lines of the trunk.

If after conversation the called subscriber N_2 should replace his receiver to the hook before the calling subscriber N_1 has replaced his receiver, the relay F becomes de-energized. The relay Y , however, remains 100 energized in a circuit over its holding winding 2. Thus a relay G is energized in the following circuit: ground, battery, relay G , working contact y_7 , back contact j_1 , ground. The relay G opens its contact g_1 so that the 105 relay P_3 becomes de-energized. Therefore, the contacts p_{10}, p_{11} and p_{15} are opened so that the called station N_2 is released. Therefore, the subscriber of the station N_2 may be 110 called by or call another party although the connector LW engages the trunk lines leading to said station N_2 . If now the calling subscriber N_1 replaces his receiver to the 115 hook the relays A_1 and B_1 in the first selector LGW are de-energized. As soon as the contact b_{12} has been closed the relay S is energized in the following circuit: ground, battery, relay S , primary off-normal contact k_7 , back contact b_{12} , ground.

This call is now metered at the end of the 120

conversation and then the talking connection between the two stations N_1 and N_2 released.

In the first selector the back contact s_1 is opened and the working contact s_3 closed.

- 5 Thus a meter relay Zr is now included in the circuit. Since the trunk line a b is grounded only at the relay O in the connector LW , this ground connection establishes a circuit for the meter bridge in the first selector 10 I.GW and for the relays A_2 , B_2 in the second selector II.GW as well as for the relays A_3 , B_3 in the third selector III.GW. The current in the relay O is thereby strengthened to such an extent that the relay O attracts its 15 armature. At the same time the meter relay Zr in the first selector I.GW is energized. Therefore, the contact zr_1 is closed and the resistance w_1 short-circuited thereby, so that the current in the test line c is increased 20 and the meter Z energized in the following circuit: ground, battery, working contact t_4 , meter Z , wiper cv , working contacts zr_1 , s_2 secondary off-normal contact wk_2 , back-contact m_1 , ground. In view of the short circuit around the relay C this relay C becomes 25 de-energized. The contacts c_4 , c_5 are opened. At the same time the following circuit for the releasing magnet M_1 of the first selector I.GW is closed: ground, battery, relay M_1 , 30 working contact s_4 , back-contacts c_6 , b_{13} , ground. When the shaft of the selector has returned to normal position the circuit for the relay S is opened at the primary off-normal contact k_7 . Therefore, the contact s_4 35 is opened and the releasing magnet M_1 de-energized. The line switch VW returns to normal position if the releasing magnet M_1 has become energized and the back contact m_1 opened.

- 40 By the energization of the relay O the connector LW is released. This releasing operation is caused by the releasing magnet M_4 being energized in the following circuit: ground, battery, relay M_4 , working contacts y_9 , o_1 , ground. As soon as the connector LW returns to its normal position the contacts k_5 , k_6 , k_8 are opened. The relays U and Y as well as the releasing magnet M_4 become de-energized. When the relay Y is de-energized 45 the circuit through the relay O is broken at the contacts y_5 , y_6 . The trunk lines a and b are now again connected with the battery over the relays A_4 and B_4 , no ground connection existing with said trunk lines either in the first selector I.GW or in the connector LW .

- 50 In the second selector II.GW the following releasing circuit is closed: ground, battery, releasing magnet M_2 , back contacts a_{11} , p_3 , b_5 , primary off-normal contact k_4 , ground, and in the third selector III.GW: ground, battery, releasing magnet M_3 , back contacts a_{12} , p_{13} , b_{14} , primary off-normal contact k_9 , ground. These releasing circuits remain established until the primary off-normal con-

tacts k_4 and k_9 are opened when the shafts of said selectors arrive at their normal positions.

If the called subscriber M_2 does not take off his receiver from the hook or if the desired subscriber's line is busy no metering takes place. In this case the relay Y is not energized. Thus the relay O is not connected to the trunk lines. If, therefore, the calling subscriber N_1 replaces his receiver to the hook the relays A_1 and B_1 in the first selector I.GW are de-energized, the relay S is energized and the ground connection broken by the opening of the back contact s_1 . Since, however, the relays A_4 and B_4 in the connector LW are not connected to ground over the relay O the meter relay Zr is not energized. Therefore, in all selectors the trunk lines are still connected to battery and the selectors return to their normal positions. 70 The relays A_4 and B_4 become de-energized. In the connector LW the following releasing circuit is closed: ground, battery, releasing magnet M_4 , back contacts y_8 , b_{15} , a_{15} , primary off-normal contact k_8 , ground. The primary 75 off-normal contact k_8 is opened as soon as the shaft of the connector arrives at its normal position. 80

85 Referring to Figures 2, 4 and 5 a telephone system is shown in which metering takes place when the called subscriber takes off his receiver from the hook. In this modification one low resistance coil of the relay Zr_1 is included in the ground connection of the contact w_4 and another coil of the relay Zr_1 in the ground connection of the contact s_1 . A slow-acting relay Q is connected in parallel with the rotary magnet D_1 . In the circuit including the resistance w_1 , by which the current in the line c is so increased that 90 the meter Z is operated, a working contact b_{16} , a secondary off-normal contact wk_4 , a back contact zr of the meter relay Zr and the back contact q of the relay Q are provided. By means of a weight GW lifted by the 95 shaft of the connector LW a bridge connection is established over the contact springs z_2 . 100

105 The meter operation takes place as follows: If the called subscriber N_2 takes off his receiver from the hook a short circuit 105 around the resistance w_1 is established over contact b_{16} , primary off-normal contact wk_4 , contact zr , contact q . The relay B_1 in the selector I.GW is energized from the time the selector is busy until the moment when the 110 calling subscriber replaces his receiver to the hook. During this time the contact b_{16} is also closed. When the rotary magnet of the selector is energized the contact q is opened and the secondary off-normal contact wk_4 of the selector is closed afterwards. If 115 the selector meets a disengaged line the relay C is energized again. The relay Q , however, remains energized for a moment and, therefore, the back contact q remains open. 120 125 130

- If the working contacts c_4 and c_5 have become closed, as described in connection with the system shown in Figs. 1—3 the following circuit is closed (see Figures 4, 2, 5): 5 ground, battery, relay A_2 , resistance w_4 , back contact p_1 , wiper j_1 , working contacts a_4 , c_4 , back contact v_2 , resistance w_6 , winding 2 of the relay Zr , back contact s_1 , ground. In this circuit the meter relay Zr is energized.
- 10 Thus the back contact zr in the short circuit around the resistance w_1 is opened before the back contact q is closed again. A holding circuit is permanently closed over either the trunk line a or the trunk line b of the 15 next selector, as described in connection with Figs. 1—3. This holding circuit is connected to ground either by the contact s_1 or the contact a_4 . The meter relay Zr thus permanently remains energized either with 20 reference to its winding 1 or its winding 2. When the called subscriber N_2 takes off his receiver from the hook, the relay Y in the connector LW is energized and the contact y_{10} closed thereby. The weight GW is released and when moving downwards temporarily closes the contacts z_2 . Both trunk lines are grounded by the contact y_{10} and the winding 2 of the relay Zr in the first 25 selector LGW is short-circuited. The relay Zr in the first selector is de-energized during the time the weight GW in the connector operates the contacts z_2 so as to be closed. In the short-circuit around the resistance w_1 the contact zr is closed and the meter Z 30 energized thereby. When the weight GW in the connector has passed the contacts z_2 the short circuit is removed and the relay Zr in the selector energized again, thereby diminishing the current in the line c .
- 35 If the called subscriber does not take off his receiver from the hook no metering takes place. Though the weight GW is lifted by the shaft of the connector and the contacts z_2 are closed by the weight no operation of the meter takes place when releasing the connector since the established connection is released by the relay B_1 in the first selector becoming de-energized. As 40 soon as the relay B_1 has become de-energized the contact b_{16} in the short-circuit around the resistance w_1 is opened. Thus it is irrelevant whether the relay Zr is still closed for some time or opened. Since the meter circuit extends symmetrically over the two 45 trunk lines the test relay of an adjacent selector is connected with the same potential so that it is not energized at the moment metering takes place.
- If it is intended to have metering take 50 place only about six or seven seconds after the beginning of the conversation with a view to enabling the calling subscriber to ascertain the number or name of the called subscriber during this time, the weight GW 55 may be provided with a retardation device

which establishes the short-circuit around the springs z_2 after said predetermined time. If the calling subscriber has ascertained that the subscriber who answers is not the required one, he induces the called subscriber 70 to replace his receiver to the hook. After this operation the relay B_1 in the first selector LGW is de-energized and the contact b_{16} in the short-circuit referred to opened so that no metering takes place. The 75 metering may be produced by means of a slow-acting relay.

I claim:—

1. In an automatic telephone system comprising telephone lines, trunk lines each having two wires, and switches and selectors for interconnecting said telephone lines with trunk lines, the combination with the trunk lines of test relays associated with the trunk lines and having coils adapted to be connected at the one end to the one talking wire of the trunk line and the other end to the other talking wire, and means associated with the trunk lines for taking reduced potential to said talking wires when the trunk line is busy; service meters associated with the telephone lines, means for interconnecting said meters with the trunk lines when the telephone line is calling, means at the called end of the connection for producing an impulse in the trunk lines when the conversation takes place, and means for transmitting said impulse to the meter for registering the conversation. 80

2. In an automatic telephone system comprising telephone lines, trunk lines each having two wires, and switches and selectors for interconnecting said telephone lines with trunk lines, the combination with the trunk lines of test relays associated with the trunk lines and having coils adapted to be connected at the one end to the one talking wire of the trunk line and the other end to the other talking wire, and means associated with the trunk lines for taking reduced potential to said talking wires when the trunk line is busy; service meters associated with the telephone lines, means for interconnecting said meters with the trunk lines when the telephone line is calling, means at the called end of the connection for producing an impulse in the trunk lines when the conversation takes place, means for transmitting said impulse to the meter for registering the conversation, and means for preventing the disconnection of the talking connection established during the flow of the impulse. 100

3. In an automatic telephone system comprising telephone lines, trunk lines each having two wires, and switches and selectors for interconnecting said telephone lines with trunk lines, the combination with the trunk lines of test relays associated with the trunk lines and having coils adapted to be connect- 110

ed at the one end to the one talking wire of the trunk line and the other end to the other talking wire, and means associated with the trunk lines for taking reduced potential to said talking wires when the trunk line is busy; service meters associated with the telephone lines, means for interconnecting said meters with the trunk lines when the telephone line is calling, means at the called 10 end of the connection for producing an impulse in the trunk lines when the conversation takes place, means for transmitting said impulse to the meter for registering the conversation, means for preventing the disconnection of the talking connection established, and means to make busy the said connections during the flow of said impulse.

4. In an automatic telephone system comprising telephone lines, trunk lines each having two wires, and switches and selectors for interconnecting said telephone lines with trunk lines, the combination with the trunk lines of test relays associated with the trunk lines and having coils adapted to be con-

nected at the one end to the one talking 25 wire of the trunk line and the other end to the other talking wire, and means associated with the trunk lines for taking reduced potential to said talking wires when the trunk line is busy; service meters associated with 30 the telephone lines, means for interconnecting said meters with the trunk lines when the telephone line is calling, a slow-acting and a quick-acting relay at the called end of the connection adapted to be energized when 35 the conversation takes place and adapted to produce an impulse at the end of the conversation when the quick-acting relay releases its armature during the retarded action of the slow-acting relay, and means for transmitting said impulse to the meter for registering the conversation.

In testimony wherof, I affix my signature in the presence of two witnesses.
